UNITED STATES PATENT OFFICE.

JOSEPH A. PENNINGTON, OF MOSCOW, IDAHO.

HORSESHOE-CALK.

1,260,028.

Specification of Letters Patent. Patented Mar. 19, 1918.

Application filed January 6, 1917. Serial No. 140,975.

To all whom it may concern:

Be it known that I, JOSEPH A. PENNINGTON, a citizen of the United States, residing at Moscow, in the county of Latah and 5 State of Idaho, have invented a new and useful Horseshoe-Calk, of which the following is a specification.

This invention relates to horseshoe calks, one of its objects being to provide a calk 10 which can be used either with or without rubber or a like plastic material.

Another object is to provide a calk which provides a firm footing and prevents the horse from slipping in any direction.

15 A still further object is to provide simple and efficient means for attaching the calk to a shoe.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

In said drawings:

Figure 1 is a bottom plan view of a horseshoe having the present improvements combined therewith;

Fig. 2 is a section on line 2—2, Fig. 1;

Fig. 3 is a section on line 3—3, Fig. 2;

Fig. 4 is an end elevation of the calk detached; and

40 Fig. 5 is a top plan view of the calk.

Referring to the figures by characters of reference 1 designates the base portion of a calk having side walls extending throughout the length thereof as indicated at 2 and 45 converging toward their free longitudinal edges. In the base 1 near one end is provided an opening 3 while a pin 4 is extended from said base near its other end, this pin, if desired, being screwed into the base, as shown particularly in Fig. 2. A longitudinal groove 5 is formed in the base and is intersected by the opening 3 therein.

A block 6 of rubber or other plastic material is arranged between the walls 2 of 55 the body and is held against displacement by frictional engagement with said walls

and also by a series of screws 7 or other fastening devices extending into the block from the base 1.

The horseshoe with which the calk is to be used, and which has been indicated at S, is provided with a pair of apertures 8 and 9 at each point where a calk is to be attached. One of these apertures 9 has its wall threaded and has seated within it the 60 threaded end of a pin 10 which projects downwardly from the shoe and is provided with a diametrical opening 11. The other aperture 8 is of such size as to receive the pin 4 of the calk.

When it is desired to attach a calk to a shoe, the anchoring pin 10 on the shoe is inserted through the opening 3 in the base of the calk, while the holding pin 4 which projects from the calk is inserted into the 75 opening 8 in the shoe. A locking pin 12 is then driven longitudinally within the groove 5 and will pass into the opening 11, thus securely fastening the calk to the shoe.

It is to be understood that the calks can 80 be applied wherever desired, it being merely necessary to provide the shoe with the openings 8 and 9 and the pins 10 at the point of attachment.

One or more of the calks can be formed 85 at each end with angular wings or spurs 13 integral with the calk and which will operate to prevent lateral slipping. Obviously the block 6 can be dispensed with if desired.

In Fig. 1 the toe calk has been shown provided with spurs 13, while the side calks are not formed with these spurs. It is to be understood that spurs may be arranged on the side calks or, if preferred, they may 95 be dispensed with on all of the calks.

Having thus described the invention, what is claimed as new is:

1. The combination with a shoe having an opening therein and an anchoring pin 100 extending from the shoe and adjacent the opening, of a calk including a base having an opening for the reception of said anchoring pin, a pin projecting from the base and insertible into the opening in the shoe, 105 a locking pin extending longitudinally of the base and through the anchoring pin projecting from the shoe, and a block of plastic material connected to the base.

2. The combination with a shoe having 110 an opening therein and an anchoring pin adjacent the opening, of a calk including

a base having an opening therein for the reception of the anchoring pin on the shoe, a holding pin extending from the base for insertion into the opening on the shoe, a locking pin extending along the base and through the anchoring pin extending from the shoe, thereby to hold the base to the shoe, walls along the sides of the base and converging outwardly therefrom, a plastic material housed between the walls and se-

cured to the base, and spurs projecting from the ends of one of the walls.

In testimony that I claim the foregoing as my own, I have hereto affixed my signature in the presence of two witnesses.

JOSEPH A. PENNINGTON.
